Inventor

By his Attorney

UNITED STATES PATENT OFFICE.

FRANK P. WEST, OF EAST HELENA, MONTANA TERRITORY.

SPIKE-EXTRACTOR.

SPECIFICATION forming part of Letters Patent No. 416,529, dated December 3, 1889.

Application filed July 11, 1889. Serial No. 317,111. (No model.)

To all whom it may concern:

Be it known that I, FRANK P. WEST, a citizen of the United States of America, residing at East Helena, in the county of Lewis and Clarke and Territory of Montana, have invented certain new and useful Improvements in Spike-Extractors; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to certain new and useful improvements in spike-extractors, the same being designed more especially for pulling railroad-spikes, but applicable to other purposes.

20 The invention is designed as an improvement upon my patent, No. 359,194, dated March 8, 1887; and said improvement consists in connecting the bifurcated block which is placed over the rail with a lever by links, so 25 that the parts will be permanently and movably connected to each other, thus preventing separation or loss of the parts, the special construction being such that the lever when properly placed can be used for placing the 30 block over the rail, as will be hereinafter fully set forth, and specifically pointed out in the claims.

In the accompanying drawings, Figure 1 is 35 a side view of my improved spike-extractor, and Fig. 2 a detail perspective view of the bearing-block and links attached thereto.

40 A refers to the handle of the lever, which is provided near its lower end with a notch or recess a , which is closed by a latch-bar B, pivoted to the lever, said latch-bar and lever having a perforation, through which can be passed a pin for locking the latch-bar to prevent the removal of the claw C, which is of substantially the same construction shown 45 in my prior patent, hereinbefore referred to. The under face of the lower end of the lever is curved, and adjacent to the ends of the terminal portions of these curves are projecting portions, the lower projection a^2 being 50 adapted to engage with a roller pivoted at the upper end of the block D. This lever, on a line with the projection a^2 , is provided

with a perforation, through which passes a bolt employed for connecting the slotted links E E to the lever A and the block D. The 55 block D is provided at its upper end with two projecting lugs d , over which are passed the lower ends of the links E, said links having perforations, and through these lugs are 60 perforations in which are inserted spring- 65 keys for holding the lower ends of the links upon the lugs. The upper ends of the links, having slots e' , are secured to the lever A by the bolt hereinbefore referred to, and beneath 70 these links and integral with the handle A 65 are bosses e^2 for the purpose of holding the same at a suitable distance from the sides of the lever. The lower ends of the links diverge slightly, which will assist in preventing side movement of the block upon the lever. 75 The upper portion of the block D has raised side walls at its front portion, and between the rear ends of these side walls is pivoted a roller F, and upon this roller the rounded portion of the lever is adapted to bear at the 75 commencement of the upward pull of the claw. At the extreme front portion of the block between the raised side walls is a stop or connecting-web. The block D is provided with a screw X, passed through one of the 80 members thereof and used for securing the block over an object, as a rail, upon which it is placed. The upper part of the links being slotted allows the lever to change the center 85 of the line of draft.

I claim—

1. The combination, with a lever carrying a pivoted claw, of a block D, bifurcated to form depending portions to bear on the base of a rail, and links E E for connecting the 90 block to the lever, substantially as shown, and for the purpose set forth.

2. In a spike-extractor, the combination of the lever A, the lower end thereof being constructed substantially as shown and provided 95 with a curved portion, a claw carried by said lever; and a block having a recessed upper face and roller and bifurcated to form depending portions to bear on the base of a rail, said block being connected to the lever by slotted 100 links E E, substantially as shown, and for the purpose set forth.

3. The combination, in a spike-extractor, of a lever carrying a claw, said lever having

- a curved lower portion and projection a^2 , slotted links connecting the lever with the block D, said block having the upper face thereof recessed to provide thereon side walls, 5 and a roller pivoted between the rear portions of said side walls, so that the curved face and projection a^2 can contact with said roller, substantially as shown, and for the purpose set forth.
- 10 4. The combination, in a spike-extractor, consisting of a lever constructed substantially as shown, a claw pivotally connected to said lever, slotted links E E, connected to the lever

in rear of the claw, and a block having an upper recessed cross-piece to which is journaled a roller, side-projecting lugs $d d$ and depending members, one of said members having an adjusting screw or bolt, the parts being organized substantially as shown, and for the purpose set forth. 15

In testimony whereof I affix my signature in presence of two witnesses.

FRANK P. WEST.
